UNITED STATES PATENT OFFICE.

WALTER HAHNEMANN, OF KITZEBERG, NEAR KIEL, AND HUGO LICHTE, OF KIEL, GERMANY, ASSIGNORS TO SIGNAL GESELLSCHAFT MIT BESCHRÄNKTER HAFTUNG, OF KIEL, GERMANY, A FIRM.

SOUND-CONDUCTING TUBE.

Application filed August 25, 1931. Serial No. 495,232.

To all whom it may concern:

Be it known that we, WALTER HAHNEMANN and HUGO LICHTE, citizens of the German Republic, and residing at Kitzeberg, 5 near Kiel, and at Kiel, county of Schleswig-Holstein, State of Prussia, Germany, have invented certain new and useful Improvements in Sound-Conducting Tubes, of which the following is a specification:

10 In ordinary sound-conducting tubes in which sound is to be conducted over considerable distances (say more than 10 yds.) the sectional area of the tubes must not be made smaller than a certain amount if the 15 sound losses caused by the tube shall not exceed the permissible extent. The requisite cross sections of the tubes are quite considerable and approximate the size of the human concha. In transmitting sound energy from such tubes to the narrow auditory 20 duct of the ear most of the sound that arrives will, if the ear is simply placed against the open end of the tube, be reflected, because a considerable congestion of the moving air will take place at the point where the sound conduit suddenly becomes narrow. The same would occur if a wide tube 25 were caused to abruptly enter into a narrow piece of tube led to the ear.

30 The problem of conducting sound waves of a definite frequency, such as are employed for instance in submarine sound signalling in an efficient manner from a wide tube into a narrow tube (such as the narrow auditory duct of the ear) is solved by the invention in two ways.

The first solution consists in inserting a tapering connecting conduit of considerable length between the wide tube and the ear, 40 the inside diameter of the one end of the tapering conduit being adapted to the section of the wide tube and the inside diameter of the other end of the said conduit being made to match with the opening of the auditory duct. Experiments have proved 45 that there is a certain most favorable length for the tapering part of the sound conduit. A short tapering piece will still produce a considerable reflecting effect and a tapering piece that is too long will be too narrow 50 at its slender end to be an efficient conductor of sound, so that an increased loss of sound energy will arise in this way. The optimum conditions are best expressed as a function

of the wave length of the sound for the 55 transmission of which the tube is chiefly used. The optimum length of the tapering conduit is about three times the length of the waves of the sound to be transmitted. Thus if sound waves vibrating at the rate 60 of 1000 per second are to be transmitted, as is often the case in sound signalling, the tapering conduit should be about 1 metre in length.

The second way of solving the problem 65 consists in interposing between the wire tube and the ear a special, small, air resonator, which is tuned to the pitch of the sound to be transmitted, and from which a small opening leads into the ear or into a narrow 70 short pipe that is led to the ear. This short pipe is introduced into the auditory duct, a so-called olive being preferably interposed between the pipe and the auditory duct. At the boundary between the resonating space 75 and the main tube there may be arranged a rigid partition with a hole of suitable size, or a vibrating diaphragm which would preferably be tuned to the sound to be transmitted.

80 Examples of the manner in which the invention may be carried out in practice are shown in the drawing in which,

Fig. 1 shows a longitudinal section of a tube fitted with a tapering connecting piece, 85

Figs. 2, 3 and 4 illustrate sound boxes interposed between the tube and the ear,

Fig. 2 being provided with an earpiece,

Fig. 3 with an olive, and

Fig. 4 a slender pipe for the auditory 90 duct.

The sound conducting tube 1, Fig. 1, through which the sound arrives from the sound apparatus which may be any suitable known device, capable of emitting tones of 95 a substantially definite frequency, merges at a certain distance from the actual earpiece 2 the narrow opening of which is connected to a piece of flexible pipe 3 that terminates 100 in an olive 4 adapted to be introduced into the auditory duct.

In the examples shown in Figs. 2, 3 and 4 a resonating chamber or box 5 is connected to the main tube 1, the interior space 105 of the box being very small and tuned to the sound employed or to the sound frequency principally occurring when the equip-

ment is used. In the arrangements shown in Figs. 2 and 3 the boundary between the resonating chamber 5 of the sound box and the tube is formed by a vibrating diaphragm 6 which is preferably also tuned. In Fig. 4 the space in the tube 1 is separated from the chamber 5 by a rigid wall 7 with an opening 8 through which the air in the chamber 5 is excited or set vibrating. The sound is conducted to the ear directly through the opening 9 in the chamber 5 in the case of Fig. 2, and through a flexible pipe 3 in the cases of Figs. 3 and 4.

We claim:—

15 1. A sound conduit for conducting sound of a substantially definite frequency, comprising several portions, each of uniform cross-sectional area but of widely different cross-section relatively to the other portion, 20 in combination with means disposed between said portions and dimensioned in ac-

cordance with the particular wave length of the sound transmitted and adapted to transfer substantially the entire sound energy from one of said portions to the other. 25

2. A sound conduit for conducting sound of a substantially definite frequency, comprising several portions, each of uniform cross-sectional area but of widely different cross-section relatively to the other portion, 30 in combination with a tube connecting said portions and gradually tapering from the large to the small cross-section and having its length dimensioned substantially three times the wave length of the sound transmitted, said tube adapted to transfer substantially the entire sound energy from one of said portions to the other. 35

In testimony whereof we affix our signatures.

WALTER HAHNEMANN.
HUGO LICHTE.
